UNITED STATES PATENT OFFICE

171,243

COIN BANK

Carl G. Bergman, Detroit, Mich.

Application June 15, 1953, Serial No. 25,509

Term of patent 7 years

(Cl. D34—11)

To all whom it may concern:

Be it known that I, Carl G. Bergman, have invented a new, original, and ornamental Design for a Coin Bank, of which the following is a specification, reference being had to the accompanying drawing, forming part thereof.

Fig. 1 is a perspective view from one side and above a coin bank showing my new design.

Figs. 2 and 3 are plan and rear views respectively of the coin bank shown in Fig. 1.

I claim:

The ornamental design for a coin bank, as shown.

CARL G. BERGMAN.
